US0D1023237S

(12) **United States Design Patent** (10) Patent No.: **US D1,023,237 S**
(45) Date of Patent: ** Apr. 16, 2024

(54) **SPRAY GUN**

(71) Applicant: **Chong Zhong**, Guangdong (CN)

(72) Inventor: **Chong Zhong**, Guangdong (CN)

(**) Term: **15 Years**

(21) Appl. No.: **29/844,107**

(22) Filed: **Jun. 27, 2022**

(51) LOC (14) Cl. **23-01**

(52) U.S. Cl.

USPC **D23/225**; D19/108; D23/226

(58) **Field of Classification Search**

USPC D23/213, 223, 225, 226, 228; D19/108, D19/115, 123

(57) **CLAIM**

The ornamental design for a spray gun, as shown and described.

DESCRIPTION

FIG. 1 is a front, right and top perspective view of a spray gun, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the spray gun that form no part of the claimed design.

1 Claim, 8 Drawing Sheets
